UNITED STATES PATENT OFFICE

2,481,299

BREATHING APPARATUS

John H. Emerson, Cambridge, Mass.

Original application December 12, 1944, Serial No. 567,806. Divided and this application August 17, 1948, Serial No. 44,659.

5 Claims. (Cl. 128—29)

1.

This invention relates to apparatus of automatic type, wherein gas, supplied under pressure, acts alternately to inflate and deflate the lungs, and designed in particular for treating patients who are unable to breathe normally, as, for example, when suffering from gas asphyxiation, drowning, or the like. The principal object of this invention is to provide a small, compact, portable resuscitator which is light in weight and which may be conveniently used in the field for first aid purposes, the present application being a division of my copending application for Letters Patent, Serial No. 567,806, filed December 19, 1944, since issued as Patent No. 2,468,741, dated May 3, 1949.

A further object of the invention is to provide a resuscitator which may be manipulated by a single attendant.

A further object is to provide a resuscitator of the automatic, pressure-actuated type, having but one flow-controlling valve.

Other objects relate to the construction and mode of operation and will be apparent from a consideration of the following description and the accompanying drawings which exemplify one embodiment of the invention chosen for purposes of illustration.

In the drawings:

Fig. 1 is a side elevation of the complete apparatus with the face mask in the position of use; and

Fig. 2 is a diagrammatic, diametrical vertical section with parts in elevation and broken away, the mechanism being shown as in the exhaling position.

For effective operation the apparatus requires a source of gas under super-atmospheric, preferably substantially constant pressure. When herein reference is made to a gas, gaseous fluid or the like, such terms are used without limiting intent, being broadly inclusive of pure gases, for example O_2 , mixtures of gases, for example atmospheric air, water vapor, etc. As here illustrated, a source of gas under super-atmospheric pressure is provided by the hand-operated plunger type pump 10 (Fig. 1). This pump is provided with a gas storage reservoir 11, the compressed gas from the pump 10 being forced through the check valve 12 on each stroke of the plunger and stored in the reservoir 11. The pressure gauge 13 indicates the gas pressure in the reservoir 11. Such a pump serves as a convenient light and portable source of gas under positive pressure for field use of the improved resuscitator device. It should be understood, however, that any other

source of gas may be used, such as a cylinder of compressed oxygen.

The operative parts of the resuscitator R (Fig. 1) are all contained in the housing H (Fig. 2). This housing, or case is hollow and externally shaped and dimensioned to permit it to be held in the palm of one hand, in effect constituting a handle for the mask M which is attached directly to the housing or casing by a short, preferably rigid, tubular connection, thus leaving the other hand free to operate the plunger of the pump. As herein employed, the term "rigid tubular connection," descriptive of the means for uniting the mask and housing, is intended to designate a connection such that the mask and housing normally occupy a substantially constant relation, even though they may be capable of slight relative movement (such, for example, as might result if the part 31 were resiliently bendable), but to exclude connections such as a substantial length of flexible tubing which would permit free relative movement of the mask and housing and which would preclude the effective use of the housing as a handle for applying the mask. Preferably this connection, between the face mask M and the resuscitator R, is of telescopic type, and such as to permit ready disconnection of the parts. The weight of the resuscitator is so small that when a patient reclines, his head can comfortably support the entire resuscitator (exclusive of the pump), its weight being distributed over the area of his face which is in contact with the face mask M.

The housing H preferably comprises two separable shells which collectively provide a chamber for the reception of the operating mechanism.

All of the operative mechanism of the device is supported by a rigid casting 20 (Fig. 2) within which certain at least of the fluid flow passages and the valve seat are conveniently formed. This casting 20 is provided with a depressed portion 21 which forms one wall of a fluid-flow chamber 22. The other wall of said chamber is formed by the flexible diaphragm disk 23 constituting the pressure-actuated element of a fluid-pressure motor which is sensitively responsive to lung pressure. The edges of this disk-shaped diaphragm 23 are secured to the casting 20 by a clamping ring G which is held in place by screws which pass through the ring and the margin of the diaphragm 23, and into the casting 20.

A valve reversing or motor chamber 30 (Fig. 2) is provided by a rigid cap member 31 which is detachably secured to the casting 20. A rigid tubular projection or nipple 37 provides the only com-

munication between the chamber 22 (Fig. 2) and the interior of the mask M (Fig. 1). The mask has a tubular member which telescopes over the outer end of the tubular member 31, thus permitting the separation of the mask and casing when desired.

Within the motor chamber 30, the valve operating mechanism actuated by the diaphragm 23 is arranged. This mechanism, together with the diaphragm or equivalent pressure-responsive element is hereinafter referred to for convenience as a "pressure motor" and may be substantially identical with the corresponding mechanism more fully disclosed in my Patent No. 2,364,626, dated December 12, 1944, or in the patent to Sinnett No. 2,268,172, dated December 30, 1931.

Briefly this mechanism comprises a toggle linkage including toggle levers T¹ and T² having their adjacent ends united by a joint, the joined ends being connected to the central part of the diaphragm 23 by a rigid strut T³. The remote ends of the toggle levers are guided for movement toward and from the casting 20 and connected by a tension spring S.

As illustrated in Fig. 2 the cap member 31 is provided with an open port 42^a leading from the chamber 30 to the outer atmosphere. To the outer surface, that is to say, the left-hand surface, as viewed in Fig. 2, of the casting 20, there is attached in a suitable manner, for instance by welding, a housing 43, which may be a casting, having within it a throat passage 63 whose delivery end registers with one end of a duct or passage 44^b in the casting 20, the passage 44^b terminating in a delivery port which opens into the chamber 30.

An aspirator device A is fixed to the outer end of part 43. This aspirator device comprises a casing within which is arranged the nozzle 46 designed to discharge a jet of pressure fluid, received through pipe 40, into the delivery throat passage 63 and thereby to aspirate fluid from the suction space 48. The suction space 48 communicates at all times by means of a tube 49^b with the chamber 22. A valve stem 51^b slides in a guide bore in a bracket T⁶ mounted on the free end of a motion-reversing lever T⁶ fulcrumed at T⁷ and pivotally connected to the toggle link T² at the point T⁸. The valve stem 51^b carries the valve 52^b at its left-hand end as viewed in Fig. 2. A coil spring urges the valve toward the left, the valve being designed at times to close the delivery port at the right-hand end of the passage 44^b.

During exhalation, the diaphragm 23 and the valve 52^b occupy the positions shown in Fig. 2. Air or gas under pressure, entering through the pipe 40, causes a partial vacuum in the suction space 48 of the aspirator, thus withdrawing air from the lungs through the mask M, the tubular connection 31, the chamber 22 and the tube 49^b, and delivering this mixture into the delivery throat of the aspirator nozzle and through the passage 44^b into the chamber 30 from which it is discharged to the atmosphere through port 42^a. When the pressure has dropped sufficiently in the chamber 22, the diaphragm moves suddenly to the left as viewed in Fig. 2, thus causing the toggle linkage to swing the lever T⁶ clockwise and thus seat the valve 52^b so as to close the delivery port at the end of passage 44^b. There is now no outlet through the delivery throat 63 of the aspirator nozzle, and consequently the gas supplied through the tube 40 backs up in the space 48 of the aspirator and

passes out through the tube 49^b into the chamber 22 and thence through the tubular connection 31 to the mask M so as to inflate the lungs. When the lung pressure reaches a predetermined amount, the diaphragm again reverses its position, the valve 52^b is opened, and the exhalation period begins. Thus, the flow of fluid through chamber 22 is reversed in direction at the end of each period of inhalation and exhalation.

While I have shown and described herein one desirable embodiment of the invention, it is to be understood that the disclosure is for the purpose of illustration only and that changes in shape, proportion and arrangement of parts and the substitution of equivalent elements may be made without departing from the spirit and scope of the work as set forth in the appended claims.

I claim:

1. An artificial resuscitator of the kind which includes a face mask, a case which houses a pressure motor including a movable element which is sensitively responsive to lung pressure and which defines one wall of a chamber, a rigid, tubular connection uniting the mask and case, said connection having a single constantly open passage affording communication between the interior of the mask and said chamber, an aspirator device, said aspirator device having a nozzle, a suction space and a delivery throat, a conduit for supplying pressure fluid to the nozzle of the aspirator, the case also housing a single reciprocating valve and snap-action means for transmitting motion from said movable motor element to said valve, the resuscitator being of the kind wherein gas under pressure supplies energy for inflating and deflating the lungs and for operating the pressure motor, characterized in that the case which houses the pressure motor and motion-transmitting means is of a size such that it may be held in the palm of one hand, a duct leading from the delivery throat of the aspirator which, at times, provides communication with the outer atmosphere, a tube, one end of which is fixed in an opening in the wall of the suction space of the aspirator and the other end of which is fixed in an opening in the wall of said chamber, the aforesaid reciprocating valve being operative to close and open said duct thereby to determine whether the pressure medium shall flow from the suction space of the aspirator to said chamber or discharge to the atmosphere, said valve and motion-transmitting means being so constructed and arranged that during exhalation gaseous medium is withdrawn from said chamber by the aspirator, and during inhalation gaseous medium under pressure is delivered directly from the suction space of the aspirator to said chamber.

2. An artificial resuscitator of the kind which includes a face mask, a case which encloses a pressure motor including a movable element which is sensitively responsive to lung pressure and which defines one wall of a chamber, a single rigid, tubular connection uniting the mask and case, said connection providing a single, constantly open passage affording communication between the interior of the mask and said chamber, an aspirator device having a nozzle, a suction space, and a delivery throat which, at times, delivers to the atmosphere, a conduit for supplying pressure fluid to the nozzle of the aspirator, the resuscitator being of the kind wherein gas under pressure supplies the energy for inflating and deflating the lungs and for actuating the pressure motor, the

case which houses the pressure motor being of a size such that it may be held in the palm of one hand, thereby to constitute a handle for use in applying the mask, characterized in having a single reciprocating valve within the case, snap-action means, also within the case, for transmitting motion from the movable element of the pressure motor to said valve, and means defining a passage for the flow of gaseous fluid to and from the mask, said passage always providing free communication between said chamber and the suction space of the aspirator device, said one valve, being operative, at times, to prevent, and at other times to permit, discharge of gaseous medium through the delivery throat, the motion-transmitting means being so constructed and arranged that during inhalation gaseous fluid flows through said chamber in one direction, and during exhalation gaseous fluid flows through said chamber in the opposite direction.

3. An artificial resuscitator of the kind which includes a face mask, a case which encloses a pressure motor including a movable element which is sensitively responsive to lung pressure and which defines one wall of a chamber, a single rigid, tubular connection uniting the mask and case, said connection providing a single, constantly open passage affording communication between the interior of the mask and said chamber, an aspirator device having a nozzle, a suction space, and a delivery throat, a conduit for supplying pressure fluid to the nozzle of the aspirator, the resuscitator being of the kind wherein gas under pressure supplies the energy for inflating and deflating the lungs and for actuating the pressure motor, the case which houses the pressure motor being of a size such that it may be held in the palm of one hand, thereby to constitute a handle for use in applying the mask, characterized in having a single reciprocating valve within the case, means, also within the case, for transmitting motion from the movable element of the pressure motor to said valve, and means defining a passage for the flow of gaseous fluid to and from the mask, said passage always providing free communication between said chamber and the suction space of the aspirator device, means defining another passage leading from the delivery throat of the aspirator device to the atmosphere, said valve being operative at times to close said last-named passage, said one valve and the motion-transmitting means being so constructed and arranged that during inhalation gaseous fluid flows through said chamber in one direction, and during exhalation gaseous fluid flows through said chamber in the opposite direction.

4. An artificial resuscitator of the kind which includes a face mask, a case which encloses a pressure motor including a movable element which is sensitively responsive to lung pressure and which defines one wall of a chamber, a single rigid, tubular connection uniting the mask and case, said connection providing a single, constantly open passage affording communication between the interior of the mask and said chamber, an aspirator device having a nozzle, a suction space, and a delivery throat, a conduit for supplying pressure fluid to the nozzle of the aspirator, the resuscitator being of the kind wherein gas under pressure supplies the energy for inflating and deflating the lungs and for actuating the pressure motor, the case which houses the pressure motor being of a size such that it may be held in the palm of one hand, thereby to constitute a handle for use in applying the mask, character- 75

ized in having a single reciprocating valve within the case, snap-action means, also within the case, for transmitting motion from the movable element of the pressure motor to said valve, the movable element of the pressure motor separating said chamber from a compartment within the case in which said valve and the motion-transmitting means are located, said compartment being open at all times to the atmosphere, the delivery throat of the aspirator device being operative, when the valve is unseated, to discharge gaseous fluid into said compartment while withdrawing air from the mask, and a duct leading from the suction space of the aspirator device to the aforesaid chamber through which gaseous medium from the aspirator nozzle flows to said chamber and thence to the mask when the valve is seated, said one valve and motion-transmitting means being so constructed and arranged that during inhalation gaseous fluid flows through said chamber in one direction, and during exhalation gaseous fluid flows through said chamber in the opposite direction.

5. An artificial resuscitator of the kind which includes a face mask, a case which encloses a pressure motor including a movable element which is sensitively responsive to lung pressure and which defines one wall of a chamber, a single rigid, tubular connection uniting the mask and case, said connection providing a single, constantly open passage affording communication between the interior of the mask and said chamber, an aspirator device having a nozzle, a suction space, and a delivery throat, a conduit for supplying pressure fluid to the nozzle of the aspirator, the resuscitator being of the kind wherein gas under pressure supplies the energy for inflating and deflating the lungs and for actuating the pressure motor, the case which houses the pressure motor being of a size such that it may be held in the palm of one hand, thereby to constitute a handle for use in applying the mask, characterized in having a single reciprocating valve within the case, snap-action means, also within the case, for transmitting motion from the movable element of the pressure motor to said valve, the movable element of the pressure motor sealing off said chamber from a compartment within the case in which the motion-transmitting means and said valve are located, the wall of said compartment having a port which is closed when the valve is seated, said compartment being always open to the atmosphere, the delivery throat of the aspirator device being aligned with and discharging gaseous medium through said port when the valve is unseated thereby withdrawing air from the mask, and a tube leading from the suction space of the aspirator device to the aforesaid chamber through which gaseous medium from the aspirator nozzle flows to said chamber and thence to the mask when the valve is seated, said one valve and motion-transmitting means being so constructed and arranged that during inhalation gaseous fluid flows through said chamber in one direction, and during exhalation gaseous fluid flows through said chamber in the opposite direction.
